UNITED STATES PATENT OFFICE

2,449,439

MERCURY INTERRUPTER

Leonard M. Wittlinger, Linden, Mich., assignor
to General Motors Corporation, Detroit, Mich.,
a corporation of Delaware

Application November 1, 1946, Serial No. 707,159

1 Claim. (CL. 200—113)

1 This invention relates to circuit interrupters and more particularly to mercury type interrupters which operate automatically when connected to a source of direct current power to make and break the circuit to provide pulsating current therein. This general type of interrupter is disclosed in United States Patent #2,107,742, issued to Samuel Ruben. In that type, one of the electrodes having an accurately defined area and formed of certain material, as an illustration carbon was placed in contact with a mercury pool, which was in turn connected to an electrode of opposite polarity. When these two electrodes were connected to a suitable source of direct current, the intensity of said current was concentrated at the surface area of the carbon member, causing the mercury in contact with that surface to be heated to the point of vaporization. This action, of course, caused the current to cease flowing, inasmuch as the resistance through the vapor was measurably greater than that through the mercury. As soon as the current had stopped, the mercury vapor recondensed into liquid mercury, completing a conductive circuit again, and the current immediately began to flow. This action, of course, is repeated, and an interrupter of pulsating action resulted.

In the type of interrupter as shown by the Ruben patent, the carbon electrode is shown as the lower one, the mercury pool being supported so that the carbon electrode projects up into the same. A similar type of interrupter is shown by the Bain Patent #2,273,921, in which a smaller carbon disc is shown in the bottom of a sealed receptacle, supported in a circular ceramic disc. A conductive electrode is swedged or otherwise permanently connected to the small carbon member, and a pool of mercury is supported above the same. However, mounting the carbon disc in a confined and restricted area has raised certain objections. In the first place, the fact that it is so closely confined prevents the carbon disc from cooling with any great degree of rapidity, and thus reduces the frequency at which the interrupter may operate. In some instances, mercury has been able to seep into pockets below the carbon electrode, causing gaseous pressures therein.

It is, therefore, an object of my invention to provide a new and novel mounting for the heating or vaporizing electrode of a mercury type interrupter.

It is a still further object of my invention to provide a mounting for the vaporizing electrode

in which rapid cooling of the same will be obtained.

It is a still further object of my invention to provide a mercury interrupter operating at a high rate of frequency.

With these and other objects in view, which will become apparent as the specification proceeds, my invention will be best understood by reference to the following specification and 10 claim, and the illustrations in the accompanying drawing, in which the drawing is a vertical sectional view through an interrupter embodying my invention.

Referring more specifically thereto, there is 15 shown an outer envelope 2 formed of glass or other suitable insulating material in one end of which there is secured an electrode 4, which projects into the interior of the envelope and carries at its upper extremity a conductive plate 20 6. An external line 8 is permanently connected to the electrode 4. A similar external line 10 is connected to an upper electrode 12, likewise permanently supported in the envelope housing, and projecting into the interior and toward the 25 first electrode. On the interior surface of the envelope there is integrally secured a cylindrical sleeve 14, concentric with the electrodes, and totally enclosing the upper one. The sleeve extends down to a greater distance than the upper electrode 12, and rigidly supports at its lower end by suitable means circular disc 16, formed of a ceramic or other insulating material.

This disc 16 has a small central aperture 18 on its upper face, and a larger aperture 20 on its 30 lower face, concentric with the first aperture, and joining the same at approximately the mid-section of the thickness of the disc. Mounted within the larger lower aperture is a disc 22, which may be formed of carbon or similar material, which is maintained in that position by suitable packing or cementing means 24 around its perimeter. The interior of the receptacle is substantially filled with mercury, which is divided into two portions 26 in the outer receptacle and 45 28 within the cylindrical portion, the level of the mercury within the center cylinder being slightly higher than that within the outer member. The glass sleeve 14 provides insulating means between the two pools of mercury.

When direct current is connected to the two outside leads 8 and 10, current flows from the electrode 6 to the mercury pool 26, thence to the carbon disc 22, to the mercury bath 28 in contact with the upper surface of the disc, to electrode 12, and out. The area of the upper surface of

the disc 22 is so designed that there will be a sufficient concentration of current at this point to heat and vaporize the mercury in contact therewith, causing the before described vaporization of the same to interrupt the current. The lower surface of the carbon disc being so much greater in area where it is in contact with the mercury in bath 26 does not have its temperature raised appreciably, and no interrupter action occurs on this face. As soon as the current is broken at the upper surface, the mercury vapor recondenes, and the circuit is again reformed to permit current flow.

However, by having my carbon disc suspended out in the center of the enclosure, the heat can be conducted therefrom rapidly, and I find that my interrupter is capable of operation at a much higher frequency than those heretofore designed. In like manner, there is no opportunity for any occluded mercury vapor behind the carbon disc to interfere with proper action of the interrupter.

The fact that the lower electrode 6 has substantial area and is mounted in proximity to the lower or cooling surface of the carbon disc also assists in cooling the latter.

I claim:

In a current interrupter, a casing formed of insulating material, a pair of electrodes mounted in spaced relation in said casing, baffle means of nonconducting material in said casing between the electrodes dividing said interior into a pair of chambers, a conductive pool of mercury in each chamber, said baffle having an aperture therein, insulating means mounted in said aperture and having concentric joining openings of different diameter extending partially through the same, a thin flat carbon member mounted in the larger opening to thus present two different surface areas to the two chambers and the conductive mercury pools partially filling each chamber.
